UNITED STATES PATENT OFFICE.

WILLIAM J. INNIS, OF OIL CITY, PENNSYLVANIA.

PULLEY.

SPECIFICATION forming part of Letters Patent No. 285,816, dated October 2, 1883.

Application filed August 18, 1883. (No model.)

To all whom it may concern:

Be it known that I, WILLIAM J. INNIS, a citizen of the United States, residing at Oil City, in the county of Venango and State of Pennsylvania, have invented certain new and useful Improvements in Pulleys, of which the following is a specification, reference being had therein to the accompanying drawings, in which—

10 Figure 1 is a vertical section; Fig. 2, a side elevation; and Figs. 3, 4, and 5 are vertical sections, showing modifications of a pulley constructed in accordance with my invention.

My invention relates to band-pulleys; and 15 the object of my invention is to construct them of paper or pasteboard disks, a wood or pasteboard rim, and a cast hub, united together, so that they shall be strong and also very light; and my invention consists in certain features of construction, hereinafter described, and specifically pointed out in the claims.

Similar letters refer to similar parts throughout the several views.

25 The hub A consists of a casting suitably bored to fit a shaft. Upon the periphery of the hub, and cast integral therewith, are one or two circular flanges, a, having one of their faces dressed radially to receive the inner edge 30 or circumference of the eye of the disks B. These disks are made of one or more thicknesses of pasteboard or of paper, glued together and pressed between forms, or in such a manner as to take and retain a concavo-convex or 35 dished form; but their inner and outer edges are preferably set at right angles to the axis of the hub and parallel to each other, to facilitate their attachment to the hub and to the rim of the wheel.

40 The disks B are secured to the circular flanges a of the hub by means of clamping-rings a' and bolts or rivets b. After being thus secured, the rim C is secured to the disk's outer edges. The rim is formed either of 45 transverse laggings c, as shown in Figs. 1, 2, and 3, united together by means of nails or pins c' passing in a tangential direction through one lagging and entering about half-

way into the other, or of segments glued or pinned together, as shown in Fig. 4, or of 50 more sheets of pasteboard coiled together and having a transversely convex face, as shown in Fig. 5.

To unite the paper disks to the rim the latter is rabbeted on the inside, adjoining the edges thereof, as shown at c², and preferably provided with grooves c⁴, to receive the edges of the disks. The central interior portion, C', of the rim is thus made to enter and be received between the two disks of the pulley, to 60 which it can then be glued, or to conveniently receive nails or screws c⁵, driven into the outer edges of said disks, to unite them securely to the rim.

In constructing pulleys I prefer to use two 65 concavo-convex paper disks extending from the rim to the double-flanged hub, as shown in Fig. 1; but pulleys may also have their hub provided with a single central flange, and one of its paper disks, as shown at B² in Fig. 70 3, may not extend to the hub thereof, but be riveted or glued, as at b, to the disk that extends from hub to rim.

Although I prefer to have the rim and disks of the pulleys constructed as shown in Figs. 1, 75 2, and 3, the form shown in Figs. 4 and 5 is also suitable for pulleys of small size.

I am aware that pulleys and wheels have been made with a central web formed of flat disks of paper, glued or otherwise united together and to the central portion of the rim, and that the metal rim of pulleys have been covered with two or more thicknesses of paper, and I do not claim pulleys constructed in this manner.

85 What I claim as my invention, and desire to secure by Letters Patent, is—

1. A pulley constructed with a cast hub, paper disks made of one or more thicknesses, and a wood rim.
2. A pulley having concavo-convex paper disks, united together as described, in combination with a cast hub and a wood rim, substantially as and for the purpose set forth.
3. A pulley having a concavo-convex paper disk extending from the hub to the rim,

and a second disk having its outer edge secured to the rim and its inner edge secured to the central web of the first disk, in combination with a cast hub and a rim, substantially as shown and described.

4. The combination of a cast hub, paper disks, constructed as shown and described, and a transversely convex rim of paper united to

10 said paper disks, substantially as and for the purpose set forth.

In testimony whereof I affix my signature in presence of two witnesses.

WILLIAM J. INNIS.
